CONCESSION ORDERING SYSTEM FOR
DRIVE-IN THEATERS

Allen B. Wilson, Galena Park, Tex.

Application January 9, 1951, Serial No. 205,095

2 Claims. (Cl. 179—1)

1

This invention relates to drive-in sound systems and more particularly a signaling circuit combined with a sound system wherein the individual car speakers may be employed for individual intercommunication with a concession booth operator.

The conventional type of drive-in theater sound system provides individual loud speakers for each customer's car and this invention provides means whereby the occupants of each car may effect a signal to appear on a central panel visible to the concessionaire with said signal being held without interruption of the program broadcast through the car speaker until the concession operator is ready to accept such order which he will do by placing the signaled car speaker in circuit with his speaker for individual communication with the car occupants. This system makes ordering from each car an easy and simple operation individualized so as not to annoy other customers of the theater. It allows the public address system to function in its normal manner except for the individual speaker being used for intercommunication which then is automatically switched back into communication with the sound track circuit on completion of the order.

Therefore it is among the objects of this invention to provide a system for using a speaker both for sound transmission from a central point and for two-way conversation between a customer and a concession stand operator.

A further object is to provide a speaker circuit connected with an outdoor theater sound distribution system for placing individualized orders for refreshments to be delivered to a car. This is accomplished by providing a panel in miniature at the concession booth having a signal light and plug receiving jack for each car stall connected with a speaker through a circuit interconnecting means capable of automatically connecting the car stall speaker for intercommunication with the booth speaker amplifying circuit.

A still further object is to provide an intercommunication system for use in conjunction with a plurality of remotely located speakers wherein the original signal is originated at one of the remote speakers.

Another object is to provide a switch mechanism capable of establishing a held signal visible in a concession booth with means for interconnecting a remote speaker of a theater amplifying system with a speaker in said booth for establishing two-way communication between the booth and signaling car.

Still another object is to provide an automatic

2

signal disconnecting means for use with an outdoor theater type of sound broadcasting system.

With the above and other objects in view as will appear as the description proceeds, my invention consists in the arrangement, combination and details of construction disclosed in the drawings and specification and defined in the appended claims.

In the drawings wherein like numerals indicate like parts in the different views:

Figure 1 is a schematic showing of a drive-in theater car parking arrangement including the circuit of the present invention.

Figure 2 is a side sectional view of an individual car speaker unit in operating position.

Figure 3 is a wiring diagram showing the present invention in conjunction with a conventional drive-in theater speaker circuit.

Figure 4 is an elevational view of a speaker unit hooked on a supporting post in an inoperative position.

Figure 5 is a detail plan view of the circuit changing switch.

Figure 6 is an elevational view of the same switch partially fragmentated.

Figure 7 is a partial view of the switch hinge.

Figure 8 is a detail sectional view of the speaker signal disconnecting switch.

Referring now in detail to the various parts as shown in the figures of the drawings numeral 10 illustrates a panel generally as being located in a concession booth 11 of a drive-in theater. The theater is provided with rows of car stalls 12 adapted to receive the cars of customers as at 13. Forwardly of the stalls 12 is located a conventional picture screen 14 spaced from a picture and sound projector 15.

Disposed adjacent each car stall 12 are provided posts 16 of suitable height and adapted to support an individual car speaker unit 17 hooked thereon as best illustrated in Figure 4 when not in use. Each of the speaker units 17 is formed with a suitable housing 18 on which is usually mounted a hook 19 adapted to fit in a hooked position over the car door glass 20 when the unit is placed in the car 13 for operation. The speakers 17 are electrically connected by a flexible cable 21 with the sound circuit 22 placed in a distribution cable system 23 that extends from the projector 15 to each post 16 where suitable plug-in facilities (not shown) may be provided. The concession booth 11 is customarily placed near the rear of the theater so that the concessionaire can fill orders for refreshments for delivery to the cars 13 by his helpers or car hops as incon-

spiciously as possible. Prior to this time it has been very difficult to signal for a desired order without annoyance to adjacent patrons of the theater.

In the present system I provide the panel board 10 located in the concession booth 11 formed as a miniature of the theater grounds with a signal light 24 and a plug-in jack hole 25 (Figure 3) numbered and diagrammatically indicated for each car stall 12. The panel 10 is provided with a bus bar 26 from which a connection 27 to each respective signal light is provided as at 28 shown schematically for purposes of simplicity of illustration. The bus bar 26 is in turn connected to a suitable rectifier 29 by a conductor 30. The rectifier 29 is connected into the circuit of this invention indicated generally by the numeral 31 which is interconnected with the sound projector by cable 32 and with the individual speakers 17 through cable system 23 as hereinafter explained.

The circuit 31 is provided with a suitable transformer 33 connected to a conventional electric distribution system as a source S of electrical supply. On the secondary side 34 of transformer 33 the rectifier 29 of conventional design is connected in order to provide direct current of suitable potential for operation of the equipment as hereinafter discussed. Obviously in case a suitable supply of direct current is available from the projecting system, transformer 33 and rectifier 29 may be eliminated.

Connected to source S by conductors 35 and 36 is a conventional amplifier 37 preferably placed in the booth 11 under control of the concessionaire. Associated with the amplifier 37 is a booth speaker 38 adapted to form an amplifier-speaker unit for use in communicating with a customer. In circuit with the amplifier-speaker unit is a suitable cut-over switch 39 adapted to alternately connect speaker 38 for listen-talk operation as hereinafter explained. Cut-over switch 39 is formed with a plurality of radially disposed contacts 40, 41, 42, 43, 44, 45, 46 and 47 between selected pairs of which parallel members 48, 49, 50 and 51 are adapted to engage to effect switching of the unit to listen-talk position as desired. Contacts 41 and 42 are connected to the input side of amplifier 37 by a pair of conductors 52 and 53. The output side of amplifier 37 is connected to contacts 45 and 46 by leads 54 and 55 respectively. The speaker 38 is connected to contacts 40 and 47 by conductors 56 and 57 respectively. Contact 43 is connected to the grounded side of the sound system by a lead 58 connected to a conductor 59 that extends between rectifier 29 and wire 60 connected to the ground side of the sound unit 62. Sound wire 60 is grounded at 61 and constitutes one side of the sound circuit electrically connecting the sound unit 62 to coil 63 of the car speaker unit 17. Contact 44 is connected by a flexible conductor 64 through a portable plug 65 adapted for insertion in hole 25 formed in the panel board representative of any particular car stall.

Plug 65 is formed with an insulated handle portion 66, a plunger 67 extending therefrom and a metal contact ring 68 secured to the forward part of the handle and disposed concentrically relative to the plunger. Ring 68 is electrically connected to conductor 64 through handle 66 to provide a circuit connecting means therethrough. Surrounding hole 25 is a second metal ring 69 engageable by contact ring 68 on insertion of the plug 65 into hole 25. The second ring 69 is electrically connected to one side of the

signal light 24 by a conductor 70. The opposite side of light 24 is connected to bus bar contact 28 through a jack switch 71 operative by a plunger 67. Switch 71 is formed with an inwardly arched flexible blade 72 preferably formed as a spring which normally engages across a pair of contacts 73 and 74 disposed in aligned spaced relationship longitudinally of the blade and connected in circuit with a resistor 75. One side of the resistor 75 is connected in the light circuit as at 76 so that engagement of blade 72 with contact 74 will place the resistor in series with the light 24 and engagement of said blade across contacts 73 and 74 will cause the resistor to be shorted out of the circuit.

The preferred form of the arched blade 72 is that of a metal spring fixed at one end to one side of the hole 25 of the panel with the other end extending across and engageable with contacts 73 and 74 with an intermediate portion 77 of the blade being exposed for contact therewith by plunger 67 on its insertion through the hole. This construction provides for movement of the blade 72 by insertion of the plug plunger 67 through hole 25 to first disengage the blade 72 from contact 73 so as to place resistor 75 in series circuit with the signal light 24 and then on further insertion of plunger 67 to effect complete disengagement of blade 72 from both of the contacts so that signal light 24 will be disconnected and caused to go out. A pressure plunger 78 is disposed in back of panel 10 adjacent each hole 25 for engagement with the plug plunger 67 for releasably holding it in an inserted position.

Conductor 70 and the side of the signal light 24 opposite from rectifier 29 are connected to a common conductor 79 and are connected into the speaker circuit through a control switch 80 provided in or attached to each car speaker unit housing 18. The control switch 80 as best illustrated in Figures 5 and 6 is formed with a fixed base 81 having an upright 82 disposed at one end, and an arm 83 pivotally connected at one end 84 to the upright by a horizontally disposed pin 85 and normally held horizontal as shown in dotted lines under urge of a spring 86. The arm 83 is formed with a pair of magnetically sensitive side portions or contacts 86 and 87 spaced apart at each side of an aperture 88 carried by arm 83 at the free end thereof forwardly of aperture 88 is a cross pin 89. Rockably mounted on the cross pin 89 as a hinged extension of arm 83 is a rectangular shaped flap member 90. Flap 90 is formed with an underslung stop member 91 disposed in parallel relationship therewith with the protruding end engageable under the ends of portions 86 and 87 of arm 83 that acts to restrict the flap to upward hinged movement relative to the arm. Secured at one end 92 to the upright 82 by suitable rivet means 93 and disposed under arm 83 is a spring member 94. Mounted for movement with spring 94 is a contactor 95 which may also be magnetically sensitive and is adapted for electrical connection with conductor 79 by a connecting lead 96 extending therefrom. Contactor 95 is secured to the under side of spring 94 and insulated therefrom by an insulating pad 97 fixed therebetween.

Mounted on base 81 in engageable relation with arm 83 and contactor 95 is an elongated electromagnetic contact unit 98 having an energizing coil 99 connected in series with contact 98 by a conductor 100 leading therefrom. Contactor unit 98 is preferably mounted on an angular

mount means 101 carried by the base 81 and adapted to provide for aligned engagement with the movable contactor 95 as well as members 86 and 87 on energization of coil 99 with said coil having sufficient holding strength to overcome the urge of springs 94 and 146 to hold the contacts in closed relationship on completion of the circuit. Completion or closure of the circuit is effected on downward movement of contactor 95 by pressure exerted thereon through a push button rod 102 positioned to extend exteriorly of the speaker housing 18 (Figures 2 and 4) for access thereto by a customer desiring to place an order.

Coil 99 is connected through conductor 103 to the grounded side 60 of the sound unit 62 through a push switch 103 positioned in the top of the support post 16, the details of which are best illustrated in Figure 8. Switch 103 is enclosed in a cap closure 111 secured to the top of post 16 by any suitable means and is provided with an upwardly extending depressible member 104 that is engageable by an arm 112 or like means carried by the speaker housing 18 and angularly protruding therefrom. Member 104 is preferably formed of insulating material and is provided with a pair of conducting members 105 and 106 horizontally disposed with spaced ends thereof engageable with aligned spaced inner contacts 107 and 108 and outer contacts 109 and 110 respectively to close the signal circuit through conductor 100 as hereinafter explained. Member 104 is held in a normally protruding position by a compression spring member 113 secured to the bottom of enclosure 111 by suitable securing means as screw bolt 114.

Base 81 is also formed with a pair of upstanding ears 116 spaced to the left of upright 82 that are spaced apart and adapted to rockably support a second rockable member 117 on suitable pivot pins 118 carried by the ears and extended through the member at oppositely spaced points. Member 117 is formed with an inner end 119 oppositely disposed from an outer end 120 with each of said ends movable in separate arcs. The two ends 119 and 120 are angularly disposed relative to each other and are adapted for limited rocking travel in their respective arcs with end 119 disposed above the base 81 engageable with the end of flap 90 and the other end 120 disposed adjacent the end of base 81.

The inner end 119 is proportioned in length so that its disengagement with hinge 90 is limited so that on pivotal movement of arm 83 flap 90 will rock arm 117 to a vertical position and then pass by end 119 prior to completion of the travel of flap 90. This rocking movement of arm 83 is under the urge of either of springs 94 and 146 and is effected on breaking of the circuit to coil 99 with rod 102 in a retracted position. Flap 90 being hinged at 89 is adapted to hinge and ride by end 119 on downward movement of arm 83 on energization of coil 99.

The opposite end 120 of rockable member 117 is formed with a vertically extending aperture 121 in which a double contactor member 122 is slidably or loosely mounted for movement therewith. Contactor member 122 formed of magnetically sensitive material is electrically insulated from the member 117 by a grommet type of insulator 123 and is electrically connected in circuit with the speaker coil 63 through a flexible tap lead 124 extending therefrom. The oppositely disposed ends of contactor member 122

are formed with contact faces 125 and 126 disposed at the top and bottom thereof respectively.

Carried by base 81 between the pivot line of 5 rockable member 117 represented by the axis of pin means 118 and vertical 82 is a mount 127 to which is anchored one end of a tension spring 128 at a point elevated above base 81 as at 130. The opposite end of spring 128 is secured to the 10 end 120 of rockable member 117 at an eye 129 carried thereby. The elevation of point 130 is sufficient relative to the axis of pins 118 to effect toggled rocking of member 117 on its being bumped past its center of travel by hinge 90 under urge of spring 94 or spring 146.

Spaced under end 120 for engagement with bottom contact face 126 on downward movement of the end is a fixed contact 131 connected in circuit with a solenoid coil 132. Adapted for 15 motivation by coil 132 for engagement with a contact 139 spaced therefrom is a movable contactor 134. Movable contactor 134 is electrically connected with the grounded side of the sound 20 system line 60 by a connecting lead 135. Lead 135 is shown tapped ahead of switch 103 at 136 to effect shunt circuit operation of the signaling means as hereinafter explained.

Spaced above contact 131 is a magnetic contact 137 provided with an energizing coil 138 connected at one side with a fixed contact 139 aligned for engagement by movable contactor 134. The other side of coil 138 is connected in 25 circuit with common conductor 79 by lead 140 which provides for energization of coil 138 through rectifier 29 on closure of contactor 134 with contact 139.

Tapped ahead of coil 138 is a by-pass conductor 141 connecting lead 140 to one side of 30 solenoid coil 132. The opposite or ungrounded side 142 of the speaker circuit extending from the sound unit 62 is connected to contact 137. The ungrounded or corresponding side of the speaker coil 63 is electrically connected to the 35 movable contact 122 through flexible lead 124. The opposite side of the speaker coil 63 is connected to the contact 107 of switch 103 by conductor 143 for closure of the speaker circuit and placing the system in operation suitable for 40 signaling the concession operator on release of pressure from button member 104 on movement of 45 the speaker unit into the customer's car as illustrated in Figure 2.

Mounted in each of the speaker housing units 50 is a conventional type of volume control 145 available for use by the customer enabling him to control the volume of sound desired either from the sound track or when listening to the concessionaire's acknowledgment of his order.

Operation of the present system starts from 55 the time that a customer of the theater parks his car 13 and removes the speaker housing 18 from its post 16. Removal of the housing 18 allows switch 103 to close so as to place the sound and signaling circuits in operative condition as shown 60 in Figure 3.

On deciding to place an order to the concessionaire the customer will press button 102 forcing contactor 95 into engagement with contact unit 98 which closes the signal circuit. Closure 65 of the signal circuit lights signal light 24 and energizes coil 99 so that the light will remain lighted on panel 10 until disconnected by acceptance of the order or until the customer replaces the housing 18 back on post 16 and thereby opens switch 103. This stay-on characteristic of the present

system is a highly desirable feature in that it provides the management with a double check as to the number of orders remaining unfilled at any one time and gives a check on speakers improperly replaced, indicated by no response to the concessionaire's answer to the signal.

It is to be noted that the speaker 17 remains operatively connected through both switches 103 and 80 allowing the customer to listen to the program being presented over the sound system until the concessionaire answers the signal. When the concessionaire is ready to take the signaling customer's order he inserts plug 65 into the hole 25 associated with light 24. The plunger 67 of the plug engages blade 72 and on bending thereof to open position opens the signal circuit. This puts out light 24 and de-energizes coil 99 allowing switch arm 83 to move upwardly with hinge 90 in its extended position engaging end 119 of arm 117 to effect toggled movement of contactor 122 into engagement with contact 131. The effect of this switching operation is to take the speaker 17 off the picture sound circuit and connect it to common conductor 79 which in turn is connected to the panel contact 69 by lead 70. Upon complete insertion of the plug 65 contact ring 68 carried thereby contacts the second ring 69 carried by panel 10 to connect the speaker coil 63 with the intercommunication cut-over switch 39.

With the switch members 50 and 51 positioned to connect with the "out" side of the amplifier 31 as shown in Figure 3 the concessionaire's voice is communicated from the booth speaker 38 to the car speaker 17 enabling him to ask for the order desired after which he moves switch 39 to the "in" or listen position enabling him to receive the order. By again switching to "out" position enables him to repeat back or acknowledge the order. Upon receiving an order 40 the concessionaire can write out a slip from which the order is filled and delivered to the car. The intercommunication part of the transaction of course will take very little time after which the concessionaire pulls out or withdraws plug 65 for use in answering the next signal for an order.

Withdrawal of plug 65 causes strip 72 to assume its normal position which is that it will first engage contact 14 closing the signal light circuit through resistor 75. This causes a diminished voltage to be placed on the car speaker coil 63 and solenoid 132. The voltage that is allowed to pass through resistor 75 is not sufficiently great as to damage the speaker coil 63 but is sufficient 50 to close contactor 134 with contact 139. With the solenoid switch 132 closed current will flow through electromagnet coil 138 in parallel with the speaker coil 63. Further removal of plug 65 allows blade 72 to bridge contacts 73 and 74 shorting out the resistor 75. The transmission of current sufficient to operate the electromagnet 138 is then effected so as to pull magnetically sensitive contactor 122 into engagement with contact 131. Contactor 122 is slidably mounted 55 on arm 117 so that it remains in contact with contact 131 until arm 117 is pulled past its center point where it will be toggled to full movement by spring 128. Full movement of arm 117 places contactor 122 in engagement with contact 137 70 so as to put the car speaker 17 back on the sound track circuit.

Breaking of the circuit to coil 132 opens contacts 134 and 139 to disconnect the shunt circuit effected during the intercommunication operation.

5 While I have described in detail the operation of my system as connected to one car speaker unit it is to be understood that the same descriptive matter applies to the other units and equipment connected forming component parts of the complete system of this invention. Furthermore inasmuch as the different applications of my system will become readily apparent to those skilled in the art it is intended that the circuit shown be illustrative and need not be limited to 10 the exact system described.

15 Thusly I do not mean to confine myself to the exact detail of construction and materials herein described and disclosed but claim all variations falling within the scope of the claims.

20 I claim:

1. In a system of the type described, the combination of a central station signal panel, a plurality of remote stations, a speaker unit at each of said remote stations, a communication circuit including a sound source connected between said central station and sound circuit each of said speaker units, a signal circuit including held signal means extending from each of said remote stations to said central panel, a control switch in said signal circuit having relay means 25 operative by said control switch to effect said held signal at said central station with said sound circuit in operation, a talking and receiving unit at said central station having switch means for connecting said unit with a signaling station, and a disconnect switch means having a resistor connected in said signal circuit to effect release 30 of said relay for automatic disconnection of the signal circuit, when said switch is opened.

35 2. In a system of the type described, the combination of a remote station speaker unit connected to a central station by means of a sound circuit, a source of sound, a signal panel having signal indicating means, a signal circuit normally open between said remote station and said panel, a source of power in said signal circuit, a magnetic sensitive switch in said signal circuit, means to energize said switch to move said switch to an energized hold position to effect a held 40 signal at said panel, a talking and receiving intercommunication unit, said means to energize said switch comprising a switch plug for connection of said intercommunication unit into said signal circuit and disconnection of said power source, a relay switch respectively connecting said speaker with the sound circuit and the signal circuit in response to a surge of power on reconnection of said power source by withdrawal of said plug from said signal circuit, and 45 resistance means for limiting said surge of power.
